UNITED STATES PATENT OFFICE.

NATHANIEL CROOKSHANK MCCLURE, OF HEALDSBURG, CALIFORNIA.

ELECTRIC ISOLATION SYSTEM.

No. 927,375.

Specification of Letters Patent.

Patented July 6, 1909.

Application filed October 18, 1907. Serial No. 398,054.

To all whom it may concern:

Be it known that I, NATHANIEL C. MCCLURE, a citizen of the United States, and resident of Healdsburg, in the county of 5 Sonoma and State of California, have invented an Improved Electric Isolation System, of which the following is a specification.

The object of this invention is to enable 10 the operator on a circuit or a line where there are a number of instruments being used, to call up or form connection with any one instrument such as a telephone, telegraph, etc. on the said circuit by ringing a bell or by 15 other signal, without disturbing the others; and when such call is answered, to enable the parties to communicate with each other without being heard by other parties on the same line.

20 In other words, my invention relates to an electric current controlling apparatus to be used in connection with telephones, telegraphs, etc.

It consists in devices whereby an operator 25 in the above named system would be able to have such full control of the electric current used that he would be able by suitable signal to call up any office or instrument upon the electric circuit without disturbing the other 30 offices or instruments on the same line, and to hold communication with the said office or instrument to the exclusion of all other offices or instruments upon the said circuit.

My invention also comprises details of construction which will be more fully explained 35 with reference to the accompanying drawings, in which—

Figure 1 is a diagram showing the general arrangement and connections for the central 40 office and four telephones representing sub-stations of a party telephone line operated over wires *a* and *b*. Fig. 2 is the front elevation of the central station indicator. Fig. 3 is a sectional side elevation of the same. 45 Fig. 4 is a horizontal longitudinal section of the same. Fig. 5 shows diagrammatically the circuits in each telephone; and Fig. 6 is a sectional view on line 6—6 of Fig. 5, of the hanger arm or switch and its contact 50 plates.

In order to accomplish the desired object, I employ what I call an isolating switch or meter *A*—Figs. 2 and 3—having a magnetic coil 2 oscillating in the space between a core 55 of soft iron, and two magnetic pillars 4, all be-

ing within the poles of permanent magnet 5. The magnetic coil 2 oscillates upon its axis and is moved by the action of an electric current passing through the coils, its proper poise being also assisted by oppositely acting 60 coil springs 6. There is also used a suitable controller *R*—Fig. 1—to regulate the electric current to be introduced. Upon the axis of the oscillating coil 2, an arm 7 of aluminum or other suitable material is rigidly 65 secured. The device is to be so constructed that the pointer thus attached to the oscillating coil will be able to describe an arc *B* of at least 90 degrees. In this arc and under the oscillating tip of the pointer, are to be 70 placed any desired number of divisions 9, the number to correspond with the number of instruments or offices on the circuit. The indicating marks or figures of the division of the arc are so placed that each will be directly 75 under the tip 8 of the pointer arm 7 as it swings over the arc. In each individual telephone or sub-station where this system is used, there is to be connected a similar device or meter *A'* with the exception that instead of there being a series of marks or figures under the pointer there shall be a magnet 9^a, each occupying a different position in the arc. In the same radial plane with the pole of this magnet, Figs. 3 and 5, but farther 80 from the oscillating coil, are placed two contact plates 10 and 10^a, of copper or other suitable material. These plates are to be placed sufficiently near the magnet so that, as the pointer moves in its arc, they will be 85 within the radial line of its tip.

Each magnet and pair of contact plates are to be secured upon a suitable frame properly fastened and so adjusted that the magnet will be within a proper sphere of influence 95 to attract the pointer as it rests over the magnet when a current of electricity is passed through the magnet so that the pointer will rest upon the said magnet, and when attracted by the magnet will rest also upon the two contact plates thereby connecting them. This magnet in each instrument is to be so adjusted that it will be, in point of location, homologous to its number in the instrument under the control of the operator at the main 100 office, but no two stations or instruments in the circuit are to have their magnets in the same homologous position. That is to say, the angular position of the radius of the contact plates and electro-magnet is different in 105 110

each instrument, and corresponds in its angle to the angle of its specific number in the arc of the central office indicator meter.

The switch arm C of each telephone—Figs. 5 and 6—is to be so constructed that it will not cause any current to short circuit, being furnished on top and bottom with plates of copper m , or other suitable material, mounted on insulation, as in Fig. 6, so located that when the lever is holding the telephone receiver, or is closed, these plates of copper will rest between the disconnected twin contact plates marked 11, 11, 12, 12, 13, 13, thus connecting the twin plates, mate to mate, and when the receiver is not on the hanger, the lever will rise by action of a spring t , and when the switch is thus opened into the elevated position, the copper plates will come into connection with the upper disconnected twin contact plates marked 14, 14, 15, 15, 16, 16, 17, 17, thus connecting these plates mate to mate. These twin plates have their two members so insulated from each other, that the mates shall not be in electrical connection except through the means thus described.

The circulation of the current is as follows, see Fig. 5. The current passes from line b and post 18 to wire d and post 19, through the meter A to post 20, wire d' , thence to contact plate 12, thence to wire c' , post 50, wire c and the ground, the operator introducing sufficient current by the controller R at the main office, to swing the pointer 7 over the position on the dial, Figs. 1 and 2, corresponding with the position of the magnet in the instrument he desires to operate or ring up. This brings the iron tip 8 of the pointer over the magnet 9^a, and contact plates 10, 10^a of the desired station, see Fig. 3. The current is then by pressing the button a^x introduced from the wire a and post 23, to contact plate 11, wire e , thence to magnet 9^a, thence to the ground wire c' , post 50 and ground. This attracts the pointer 8 so that it rests upon the magnet and the contact plates 10 and 10^a, thus connecting the plates 10 and 10^a. A current from the cells n then flows through f and e to contact plates 11, thence to contact plates x , thence over e' to contact plates 10 and 10^a, thence to contact plates 13, thence by wire f' to the bell coils O, or other signaling instruments, thence back by wire f'' to the battery cells n , causing such signals as the operator may give by making and breaking the circuit a . When the receiver is taken from the switch arm C, the arm at once rises and opens the switch, and when the switch is opened, it breaks all connections at the twin contact plates marked x , 11, 12 and 13, and makes contact with twin plates 14, 15, 16 and 17. The bell O, or signaling instrument, stops acting and the pointer 7 would at once drop back to zero were it not that the current through wire d

from post 18, passing through the meter at 19, 20, is intercepted at W , and is carried over d^2 to contact plates 17, which are so arranged that they will receive the plates on the switch before it has broken connection at 70 plate 12, thus the current is not allowed to break, but passes over d^3 and on to the ground wire c' , and thus continues to hold the pointer over the magnet 9^a, and the plates 10 and 10^a. The current from the 75 cells n passes over f to the magnet 9^a, thence over g to contact plates 16, back over g' , and f^2 , thence to the cells n which gives continuous attraction of magnet 9^a for the pointer tip 8, and thus continues the contact for 80 plates 10 and 10^a as long as the switch arm is in this position. The current from 23 now goes to contact plate 14, thence through e' to the contact plates 10 and 10^a, thence through e^2 to transmitter D of telephone (or telegraph) thence to contact plates 15, through e^5 , to receiver E (or sounder) thence through e^4 and binding post 50 to the ground wire c . In order to ring up central or main office, the receiver E is left on the hanger, with the 90 switch left closed, and the call is made to central by a given signal assigned to each office by pressing the button marked S, which is so arranged that when pressed it breaks the connection with the receiver E 95 and transmitter D, and makes a connection with the battery from 23 to the ground wire, thus sending the current over the wire a , which in turn rings a bell or buzzer at central giving the number of office desiring communication.

The wire which connects the button S with the receiver wire, passes through a contact plate which is connected by a plate on pointer 7, while it rests at zero but is disconnected as soon as the pointer moves away from zero and begins to swing in its arc. This prevents calling central while the line is in use or the accidental ringing of bells as the pointer passes over their magnets in the arc. 105 These plates should be so arranged that they will not retard the free movement of the pointer 7, and are to be insulated. The isolating switch may be inclosed in a box which is kept locked to prevent tapping the line or 110 operating switch by hand. There may be a glass in front of switch making it visible so it can be seen when the line is in use by observing the pointer. This system may be applied to communication systems without an exchange, by simply using the controller and batteries as shown in Fig. 1, at each office or station or in connection with an exchange by connecting the two main wires a and b , to their proper places in the switch board, 115 and the connections made from one division to another by double contact plugs. When no exchange is used and each office or station has a controller, etc., tapping the lines may be prevented by the operator introducing 120

sufficient current to swing the pointer 7 clear past all contacts on the arc, thus no one else can use their controller and batteries to increase the current so as to make their own connections. For sending a general message to all stations there may be a second magnet placed in the arc under the pointer farthest from zero, and this may be made to operate all the instruments at once, its two contact plates and magnets being similarly connected to 9^a, 10 and 10^a. However this is optional as the central may call up all of the line at one time by opening the circuit *a* first, and then opening the isolating current *b* as far as desired.

In places where it is desired to operate individual power or light appliances or fixtures of any kind without disturbing other apparatus on the same system it may be done by applying the connection shown at the switch arm while closed, as shown in Fig. 5. Letting the batteries *n* represent a source of power, and let the bells *O*, or their position in the circuit, represent such instruments or appliances as is desired to operate, they may be operated so long as the current is sent over the wire *a* to magnet 9^a.

By the use of my electric isolation system, party lines may be used largely, thus obviating the necessity of great expense of constructing a large amount of wiring and still giving as complete isolation to the subscriber as does an individual line.

I claim:

1. In an electric isolation system comprising telephone telegraph and power circuit controllers the combination of a central office indicator meter, having an electro magnetically deflectable arm and marks for indicating the amount of deflection, a current controller for regulating the amount of deflection, and an electric circuit, a series of substation instruments thereon, each having a similar electro magnetically deflectable arm, a second circuit, an electro magnet and two contacts, said electro magnet of each substation being placed in the radial line of the deflectable arm, but in a different angular relation, to the magnet in every other substation, and in homologous relation to the indicator marking at the central office meter corresponding to that of said substation, and connected in series in the said second circuit, an armature mounted on the end of the deflectable arm, two contacts by the said magnet, each substation's electro magnet being arranged near the plane of deflection of the deflectable arm, to attract the said armature and close the contacts whenever the specific and individual amount of deflection of any substation arm has been obtained, through the controller, the amount of current

being indicated in the central office meter and the current upon which the said magnet is located being closed by the operator at the central office.

2. In an electric isolation system, comprising telephone, telegraph and power circuit controllers the combination of a central office indicator meter having a magnetically deflectable arm and marks for indicating the amount of deflection, a current controller for regulating the amount of deflection, and an electric circuit, a series of substation instruments thereon, each having a similar electro magnetically deflectable arm, a second electric circuit and a series of electro magnets, one at each substation, the said electro magnet of each substation being placed in the radial line of the deflectable arm but in a different angular relation to every other magnet in the series and in homologous relation to the indicator markings of the central office, corresponding to the said subscriber and near the plane of deflection of the deflectable arm, an armature carried by the deflectable arm, two contacts by the said magnet, each subscriber's electro magnet being arranged to attract the armature carried by the deflectable arm and close the contacts whenever the specific amount of deflection of any subscriber's arm has been obtained through the controller and indicated by the meter arm at the central station and the said second circuit is closed, a source of electrical energy in each of the said circuits, the said contacts by the magnets being connected with shunts on which are located instruments of communication and signaling.

3. An electric isolation system, comprising a central office indicator meter having an electro-magnetically deflectable arm having on its axis an oscillating coil, oppositely acting springs for balancing the same, a permanent magnet with poles embracing the coil, a graduated plate with markings for indicating the amount of deflection of the arm, a current controller for regulating the amount of deflection, a telephone circuit, and a series of subscribers' instruments thereon, each having a similar electro-magnetically deflectable arm and coil, and an electro-magnet and two contacts, said electro-magnet of each subscriber being placed in the radial line of the deflectable arm but in a different angular relation to every other subscriber and in a homologous relation to the indicator markings at the central office corresponding to that of said subscriber.
